*Primary Examiner—James M. Gandy**Assistant Examiner—Melody Brown**Attorney, Agent, or Firm—Leon Gilden*[57] **CLAIM**

The ornamental design for a chock block unit, as shown and described.

DESCRIPTION

FIG. 1 is a front elevational view of a chock block unit showing my new design, it being understood that the broken lines are for illustrative purposes only and form no part of the claimed design;

FIG. 2 is a rear elevational view thereof;

FIG. 3 is a greatly enlarged left side elevational view thereof;

FIG. 4 is a greatly enlarged right side elevational view thereof;

FIG. 5 is an enlarged top plan view thereof; and,

FIG. 6 is an enlarged bottom plan view thereof.

FIG. 1

FIG. 2

FIG. 3

FIG. 4

FIG. 5

FIG. 6
